UNITED STATES PATENT OFFICE.

CHARLES VERNER LINDBLAD, OF BROOKLYN, NEW YORK, ASSIGNOR TO AMERICAN MACHINE & FOUNDRY COMPANY, A CORPORATION OF NEW JERSEY.

AUTOMATIC FEED MECHANISM FOR INDIVIDUAL-CIGARETTE MACHINES.

Application filed November 13, 1925. Serial No. 38,751.

This invention relates to an improved automatic feed mechanism for individual cigarette machines, either of the paper wrapper type, or of the all-tobacco type sometimes called little cigars; and it has for its main object the production of a device designed and adapted for use in connection with individual cigarette machines of the rolling table type, said device comprising means for automatically and continuously feeding tobacco, and means for intermittently interrupting the delivery of the fed tobacco, while the cigarette machine is rolling a cigarette from previously delivered tobacco. With this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a side elevation of a mechanism constructed in accordance with the invention; Fig. 2 is a plan view of the structure shown in Fig. 1; Fig. 3 is a sectional elevation of the structure shown in Figs. 1 and 2; Fig. 4 is a front elevation, partly in section, of the structure shown in Figs. 1, 2 and 3; and Fig. 5 is a detail sectional view, on an enlarged scale, of the lower feed belt and side walls of the hopper.

In carrying the invention into effect, there is provided means for automatically and continuously feeding tobacco from a mass of a width slightly greater than the length of the individual cigarettes to be made, and means for intermittently interrupting the delivery of the fed tobacco to an individual cigarette machine in connection with which the mechanism is used, in order to give time for the said machine to roll a cigarette in a wrapper before it receives more tobacco for a succeeding cigarette. In the best constructions contemplated, the interrupting means is actuated by a moving part of the cigarette machine. In the best constructions also, there is provided a delivery throat to which the feeding mechanism continuously delivers tobacco, and chute walls below said throat and movable to temporarily close said throat to interrupt delivery of the fed tobacco. These parts and means may be varied in

construction within the scope of the claims, for the particular device selected to illustrate the invention is but one of numerous possible concrete embodiments of the same. The invention, therefore, is not to be restricted to the precise details of the specific structure shown and described.

Referring to the drawings, 6 indicates a hopper into which the cigarette tobacco is dumped from time to time as it is automatically and continuously fed out of said hopper by means of a forwarding belt 7 which coacts with a picker roll 8 to continuously feed tobacco into a throat 9 below said picker roll. The entire mechanism for continuously feeding the tobacco is of the now well known Bronander type, and since its specific construction lies wholly outside the limits of the present invention, a detailed description thereof, being unnecessary to a full understanding of the present invention, is omitted in the interest of brevity and clearness.

Hinged at 10 to the front of the throat 9 is a front chute wall 11; and hinged at 12 at a lower level than 10, is a rear chute wall 13. The chute wall 11 is normally held in the position shown in Fig. 3 by means of a coiled spring 14 surrounding the pintle on which said wall is hinged at 10. The chute wall 13 is normally held in the position shown in Fig. 3 by means of a coiled spring 15 surrounding the pintle on which said wall is hinged at 12. The rear wall 13 carries a shoe 16 which lies in the path of a cam-plate 17 secured to the rolling frame of the individual cigarette machine in connection with which the device is used, and moving with it. This rolling frame is indicated in full lines in retracted position, and in dotted lines in projected position, in Fig. 3.

When the parts are in the positions shown in full lines in Fig. 3, the throat 9 is open and tobacco is falling through the chute between its walls 11 and 13 to the pocket 18 of the chianti belt 19 of the cigarette machine. As the cam-plate 17 moves forward, however, it engages the shoe 16, and, by means of the same, swings the rear wall 13 forward into engagement with the front wall 11 which the former pushes before it, both swinging forward and upwardly until, at the end of the forward movement of the cam-plate 17, they occupy the positions shown by the dotted lines in Fig. 3. When

the parts reach this position, the throat 9 is closed and tobacco begins to accumulate on the upper surface of the rear wall 13, then forming a closure for the throat 9. As the 5 cam-plate 17 retreats, the springs 14 and 15 return the chute walls to their normal positions, thus again opening the throat to permit the accumulated tobacco to fall through the chute to the pocket of the chianti belt 10 for another cigarette. The cycle of operations is then repeated.

What is claimed is:

1. An automatic feed mechanism for individual cigarette machines having a reciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations.

2. An automatic feed mechanism for individual cigarette machines having a reciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations, said means having an actuating member in the path of and controlled by a moving member of said device.

3. An automatic feed mechanism for individual cigarette machines having a reciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations, said means including a tobacco delivery throat and movable chute walls opening and closing said throat.

4. An automatic feed mechanism for individual cigarette machines having a re-

ciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations, said means including a tobacco delivery throat and hinged chute walls below said throat and normally lying in the path of and actuated by a moving member of said device.

5. An automatic feed mechanism for individual cigarette machines having a reciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations, said means including a tobacco delivery throat, a front chute wall hinged to the front of said throat, a rear chute wall hinged to the rear of said throat at a lower level than the front wall hinge, and a shoe behind said rear wall and normally lying in the path of and actuated by a moving member of said device.

6. An automatic feed mechanism for individual cigarette machines having a reciprocating cigarette rolling device, comprising mechanism for automatically and continuously feeding shredded tobacco in a shower, and means actuated by said device and alternately operating to guide the showered tobacco to said device between cigarette rolling operations and to withhold it therefrom during said operations, said means including a tobacco delivery throat, hinged chute walls below said throat and normally lying in the path of and actuated by a moving member of said device, and springs for returning said walls to normal position after displacement by said moving member.

In testimony whereof, I have signed my name to this specification.

CHARLES VERNER LINDBLAD.
